UNITED STATES PATENT OFFICE.

THOMAS M. EYNON, OF PHILADELPHIA, PENNSYLVANIA.

OPERATING MEANS FOR LIQUID-LEVEL INDICATORS.

Application filed March 19, 1921. Serial No. 453,840.

My invention relates to means for operating indicators at the dash-board of an automobile to show the height of gasoline in the tank.

- 5 The purpose of my invention is to use a float having a relatively small vertical extension and to transmit its vertical movement through a belt, which may be a chain driven directly by movement of the float.
- 10 A further purpose is to rotate gearing by belts operated by a float and to connect the gearing with a diaphragm-operated indicating mechanism.

- 15 A further purpose is to use several belts driven by the float and assisting each other in the rotation of gearing, which rotation is transmitted to fluid indicating means at the dash-board.

Further purposes will appear in the specification and in the claims.

I have preferred to illustrate my invention by but one form, among the various forms in which it might appear, selecting a form which is practical, efficient and very reliable and which at the same time well illustrates the principles of my invention.

Figure 1 is an outline view of an automobile to which a preferred form of my invention is applied.

30 Figure 2 is a section upon line 2—2 of Figure 1.

Figure 3 is a section upon line 3—3 of Figure 2.

35 Figure 4 is a section upon line 4—4 of Figure 3.

In the drawings similar numerals indicate like parts.

Describing the form shown:—Within the tank 5 I mount operating mechanism, insertable and removable in its entirety by insertion or removal of a bottom closure herein-after described for controlling a fluid indicator 6 through a fluid, preferably a liquid within pipe 7. The indicator may be of the sight type or may operate by pressure or in any other recognized way.

The tank may be of any shape. In order to accommodate the operating mechanism, I cut openings 8 and 9 in the top and bottom, 50 which are closed by a cap 10 and a bottom closure 11 each preferably giving room above or below the tank for operating parts. I retain the cap and bottom closures by any suitable flanges 12, 13 united to the tank, 55 and mount the operating mechanism upon

one of these closures, preferably upon the lower closure as shown.

This lower closure is shown as recessed below the tank at 14 to receive a preferably ring-like type of float 15, having a relatively small vertical extension.

Upon the lower closure I mount standards 16 and 17 which carry diaphragm-supporting flanges 18 and 19. Their faces afford seats for diaphragms 20 and 21, held in place by rings 22 and 23. The spaces 26 and 27 to the left and right respectively of these diaphragms are closed by the standards 16 and 17, which are apertured to receive removable plugs 24 and 25. Setting up or slackening these plugs adjusts the capacities of the spaces and, consequently the quantities of fluid within these spaces, varying the "setting" of the gauge. This fluid is preferably liquid and may be alcohol or any other liquid which will not freeze at the temperature to which it is to be exposed and which can be seen in the sight gauge or which will operate a pressure gauge.

Upon the upper ends of the standards 16 and 17 I mount rods or strips 28 and 29 which support the upper frame work 30. This frame work carries pulleys, sprockets or other wheels which are for flexible connections and are shown at 31 and 32 upon shafts 33 and 34. I call these belts, intending to cover the many forms of bands, cords, chains, etc. by this language.

These shafts are equipped with spur gears 35 and 36 which engage a crank gear 37 upon shaft 38. The shafts are suitably supported in the frame.

Upon gear 37 I place a crank pin 39 to which is pivoted the upper end of pitman 40.

Upon the closure 11 I mount ears 41 supporting two pulley wheels, sprocket wheels or other band wheels 42 and 43 which turn upon shafts 44. Two are used in agreement with the wheels 31 and 32 and in order to balance the construction as best seen in Figure 3. The wheels 42 and 43 are connected with wheels 31 and 32 by means of the belts 45 and 46 which are connected with the float by engagement at 47, 48 with arms 49 and 50 connected with the float. It will be noted that pulleys 31 and 32 must rotate in the same direction and that connections between the belts 45, 46 and the float must, therefore, be made on corresponding stretches of the belts or bands. For this

100

105

110

reason connection is made with the left stretch of the belt in each case.

The lower end of pitman 40 is connected at pivot 51 with the two arms 52, 53 of a toggle. These arms are connected at 54 with ears 56 and 57 mounted upon the diaphragms 20 and 21. Though I recognize that the same operating mechanism could be used with balanced diaphragms, shown in a co-pending application for operating means for liquid height indicators, Ser. No. 459,389, filed March 19, 1921. The construction here shown causes the diaphragms to be moved in opposite directions. By this means the quantity of flow is doubled since the combined flows from two diaphragm chambers are united; but the fluid content of the tank is varied with movement of the diaphragms, resulting in a loss of balance. Both of the spaces 26 and 27 would in that case be connected with the pipe 7, or one only may be so connected as preferred.

In operation as the float moves upwardly from the position shown in Figure 3, it moves the left hand stretches of both of the belts 45 and 46 upwardly, rotating both of gears 31 and 32 in the same clockwise direction (Figure 3) and rotating the gear 37 in a counter-clockwise direction. This rotates the pin 39 and with it the pitman 40, straightening the toggle and pushing the diaphragms away from each other, with consequent reduction of the cubical capacities of the spaces 26 and 27.

This raises the fluid in the sight gauge—if one be used—or increases the pressure in the pressure gauge—if it be preferred—giving the desired indication. In the reverse operation lowering of the float lowers the left hand stretches of the belts turning the wheels 31 and 32 in counter-clockwise direction and the gear 37 in clockwise direction. This loosens the toggle, draws the diaphragms toward each other and allows the liquid within the indicator connections to flow into the space or spaces back of the diaphragms with which the indicator is connected.

In this illustration, and as suggested above, I have disregarded the variation in cubical contents of the remainder in the tank by reason of movement of both diaphragms together, since this matter has been taken care of properly in a co-pending application filed by me in which the two diaphragms are joined by a connection so as to move together and one end of the toggle is fixed, maintaining the cubical contents to the tank unchanged. Such an arrangement may, of course, be applied to the present invention where maintenance of cubical contents of the tank is desired.

I recognize that my disclosures herein will suggest to those skilled in the art various other forms of obtaining the advantage of my invention, differing in this suggestion ac-

cording to the needs, prior experience and whim or preference of the designer. It is my purpose to include herein all such variations of my invention, whether securing all or a part only of the benefit thereof, which come within the reasonable spirit and scope of my invention.

Having thus described my invention, what I claim as new and desire to secure by Letters Patent is:—

1. In an indicating device for gasoline tanks, a tank, two pairs of guide wheels, one of each pair mounted in the bottom and the other in the top of the tank, supports for the wheels, separate belts about the wheels of the two pairs, a float surrounding the belts, connection from the float to each of the belts, gearing connected with the upper wheel of each pair and depth-indicating mechanism operated from said gearing.

2. In an indicating device for gasoline tanks, a tank, two pairs of guide wheels, one of each pair mounted in the bottom and the other in the top of the tank, supports for the wheels, separate belts about the wheels of the two pairs, a float surrounding the belts, connection from the float to each of the belts, gearing connected with the upper wheel of each pair and depth-indicating mechanism operated from said gearing, the indicating mechanism so interconnecting with the gearing as to maintain the same movement of one belt as of the other and hence equal movements of all the parts of the float connected therewith.

3. In an indicating device for gasoline tanks, a depth indicator, a gear and connections from said gear to the depth indicator, a pair of separated operating gears engaging the first gear, shafts for the three gears, supports for the shafts, a tank, wheels upon the shafts of the operating gears located in the upper part of the tank, a pair of wheels in the lower part of the tank, a pair of bands each trained about one wheel of each pair, the wheels of each band being different from those of the other, and a float surrounding the bands and engaging both of them.

4. A tank, standards in the bottom of the tank having facing spaces surrounded by seats, diaphragms upon the seats closing the spaces so as to confine a pressure fluid therein, toggle levers each pivotally connected to the other at one end and at the other end to a corresponding diaphragm, a rod connecting with the toggle levers, a gear with which the rod is connected to reciprocate the rod with movement of the gear, float-actuated means for turning the gearing to move the rod, a pressure responsive indicator, and fluid conveying means connecting the same with one of the spaces to cause the pressure fluid therein to actuate the indicator in response to movement of its diaphragm.

5. In an indicating device for gasoline tanks, a tank, a float, a continuous belt operated by vertical movement of the float, gearing driven by the belt, a diaphragm, means whereby said diaphragm is enclosed on one side to form a space free from communication with the tank, a fluid-operated indicator, connections establishing fluid communication between the indicator and said space, said connections including a toggle between the gearing and the diaphragm to contract the space with upward movement of the float.

6. In an indicating device for gasoline tanks, a tank, a float, a continuous belt operated by vertical movement of the float, gearing driven by the belt, a diaphragm, means whereby said diaphragm is enclosed on one side to form a space free from communication with the tank, a fluid-operated indicator, connections establishing fluid communication between the indicator and said space said connections including a toggle and also a crank turned by the gearing, between the gearing and the diaphragm to contract the space with upward movement of the float.

7. In an indicating device for gasoline tanks, a tank, a pair of opposed diaphragms and mounts therefor including means whereby the diaphragms are enclosed on one side to form spaces free from communication with the tank, a toggle connecting the diaphragms, a pitman connected at one end with the toggle, a crank for said pitman, gearing turning the crank, a belt operating

the gearing and a float connected with the belt to move it with movement of the float.

8. In an indicating device for gasoline tanks, a tank, a pair of opposed diaphragms and mounts therefor including means whereby the diaphragms are enclosed to form spaces free from communication with the tank, a toggle for the diaphragms, a pitman connected at one end with the toggle, a crank for said pitman, gearing turning the crank, a belt operating the gearing and a float surrounding the diaphragms and pitman and connected with the belt to move it with movement of the float.

9. In an indicating device for gasoline tanks, a tank, a diaphragm actuator within the tank, a diaphragm therefor a mount for the diaphragm providing a fluid space between it and the diaphragm, gearing and connections for moving the diaphragm, a float a plurality of belts connected with and providing the guide for the float, a pair of wheels for each belt about which it is trained and connections between one wheel of each belt and the gearing for operating the latter with movement of the belts.

10. In an indicating device for gasoline tanks, a tank, a diaphragm therein, a support for the diaphragm providing a space closed by the diaphragm, a float surrounding the diaphragm in one position of the float, a belt and connections from the float to the diaphragm including a belt-operated crank pin moving the diaphragm back and forth with lifting or lowering of the float.

THOMAS M. EYNON.
